UNITED STATES PATENT OFFICE.

MANO S. SLENKER, OF SAN FRANCISCO, CALIFORNIA.

STROPPING-MACHINE.

1,188,687.

Specification of Letters Patent. Patented June 27, 1916.

Application filed November 6, 1915. Serial No. 59,979.

To all whom it may concern:

Be it known that I, MANO S. SLENKER, a citizen of the United States, residing at San Francisco, in the county of San Francisco and State of California, have invented new and useful Improvements in Stropping-Machines, of which the following is a specification.

The object of the present invention is to 10 provide an improved machine for stropping razors.

In the accompanying drawing, Figure 1 is a broken plan view of my improved stropping machine; Fig. 2 is a longitudinal vertical section; Fig. 3 is a cross sectional view.

Referring to the drawing, 1 indicates a suitable base on the front and rear ends of which are erected yoke-shaped standards 2, in the sides of which are bearings for the 20 ends of parallel shafts 3, carrying cylinders 4 on which are secured hollow adjacent cylinders 5 of leather, each cylinder having a longitudinal series of transverse circular flanges or rings 6 and grooves 7 between the 25 rings. The cylinders are so arranged on the shafts that the rings of each cylinder are opposite to the grooves 7 of the opposite cylinder. Having its ends secured in the upper portions of the yokes is a bar 8 from 30 which depend slidable hangers 9, to which are secured, by screws 11 and thumb nuts 12, clamping plates 13 between which a razor blade 14 can be clamped. Secured to, and extending forwardly from, the front hanger 35 9 is a fork-shaped arm 16, in which is pivoted, as shown at 17, one end of a pitman 18, the other end of which is pivoted on a shaft 19 extending eccentrically through the bottoms 21 of cup-shaped crown wheels 40 22 the teeth 23 of which mesh with the teeth of pinions 24 secured upon the forward ends of the shafts 3. Said crown wheels are centrally secured to square shafts 26, having rounded portions 27, which rotate in bearings 28 supported by brackets 29 secured to

the front standard 2 and to the base 1. One of said shafts 26 extends outwardly beyond its bearing, and to its outer end is secured a crank handle 31. A razor blade having been inserted between the clamping plates in the 50 proper position so that its lower edge extends between the circular leather rings 6 of the two series, and the thumb nuts being screwed up so as to clamp the razor in said position, the crank handle is rotated, which 55 produces a rotary motion in opposite directions of the two series of rings, and at the same time produces a longitudinal motion of the razor blade between the rings. By this means a very effective abrasive action is 60 caused, thus producing a sharp edge on the razor blade.

The advantages of the apparatus are the ease and convenience of operation, and the simplicity and economy of construction. 65

I claim:

The combination of a base, standards thereon, shafts having bearings in said standards, abrasive cylinders and pinions on said shafts, two outwardly facing cup-shaped crown wheels meshing with said pinions, both rotatable about the same axis but on different shafts transverse to said shafts, a guide secured to said standards, means 70 slidable on said guide for securing a cutting instrument, a shaft extending eccentrically through the bottoms of said crown wheels, and a pitman, of which one end is connected to said last-named shaft and the other is connected to said means whereby a longitudinal 75 reciprocating movement is imparted to said means with the rotation of said crown wheels. 80

In testimony whereof I have hereunto set my hand in the presence of two subscribing 85 witnesses.

MANO S. SLENKER.

Witnesses:

F. M. WRIGHT,
D. B. RICHARDS.
